UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 14, 1925, Serial No. 15,615. Renewed June 29, 1929.

My invention relates to mining machines. An object of my invention is to provide an improved mining machine. Another object of my invention is to provide a mining machine having improved feeding means. A further object of my invention is to provide a flexibly fed mining machine slideable on its own bottom on a mine bottom wherein improved means are provided for controlling movement of the machine during the various operations thereof. Still another object of my invention is to provide an improved mining machine of the flexibly fed type having advance and receding flexible feeding portions wherein improved variable speed means are provided to act on said portions to control movement of the machine during the various operations thereof. Still another object of my invention is to provide an improved mining machine of the invertible type presenting parallel plane supporting surfaces wherein the machine may selectively operate on one surface as an undercutter or may be inverted and operate on the other surface as an overcutter. Another object of my invention is to provide an improved mining machine of the flexibly fed type wherein improved interchangeable means are provided, whereby the machine may be selectively utilized with a continuous flexible feeding member or with separate flexible feeding members. Still another object of my invention is to provide an improved flexibly fed mining machine of the convertible chain or wire rope type having improved and simplified means whereby the parts may be interchanged with facility and for guiding the feed chain or the feed rope. Still another object of my invention is to provide an improved mining machine of the flexibly fed type having improved driving and guiding means for the flexible feeding member. A still further object of my invention is to provide an improved mining machine having improved means for guiding the machine during longitudinal movement thereof and for guarding the cutter bits of the rapidly moving cutter chain. Still another object of my invention is to provide an improved mining machine having im-

proved truck driving means therefor. Another object of my invention is to provide an improved mining machine of the flexibly fed room and pillar type wherein improved feeding and cutting mechanism of an exceedingly simple and compact character is provided, thus producing a machine of relatively low height especially adapted to use in low vein work. A further object of my invention is to provide a mining machine operable to cut in opposite directions having an exceedingly simple and compact general arrangement of parts. These and other objects and advantages of my invention will, however, hereinafter more fully appear.

In the accompanying drawings I have shown for purposes of illustration two forms which my invention may assume in practice.

In these drawings,

Fig. 1 is a plan view of a mining machine 70 constructed in accordance with one embodiment of my invention, the view being partially broken away in section to facilitate illustration.

Fig. 2 is a side elevational view of the machine shown in Fig. 1.

Fig. 3 is an elevational view of the front or cutter bar end of my improved mining machine, the view being partially broken away in section to facilitate illustration.

Fig. 4 is an end elevational view of the rear or feeding end of my improved mining machine.

Fig. 5 is a side elevational view of the machine illustrated in its inverted or overcutting 85 position.

Fig. 6 is a detail sectional view taken substantially on line 6—6 of Fig. 1, illustrating a portion of my improved sumping guide and cutter chain guard.

Fig. 7 is a transverse horizontal sectional view taken substantially on line 7—7 of Fig. 4, the view being shown partially in plan.

Fig. 8 is a detail transverse vertical sectional view taken substantially on line 8—8 of Fig. 2 illustrating a portion of the improved guiding means for the flexible feeding member.

Fig. 9 is a detail sectional view illustrating 100

a portion of my improved sumping device and cutter chain guard.

Fig. 10 is a detail view, partially in section, illustrating a portion of my improved feed clutch controlling mechanism.

Fig. 11 is a central longitudinally extending vertical sectional view taken substantially on line 11—11 of Figs. 1 and 7, the view being shown partially in side elevation.

Fig. 12 is a developed horizontal sectional view of a detail of my improved cutter chain clutch controlling mechanism.

Fig. 13 is a transverse vertical sectional view taken substantially on line 13—13 of Fig. 11, the view being partially shown in elevation.

Fig. 14 is a side elevational view similar to that shown in Fig. 2 illustrating the machine when adapted to use with a plurality of wire feed ropes.

Fig. 15 is a partial plan view of the machine shown in Fig. 14, the view being shown partially in section to facilitate illustration.

Fig. 16 is a plan view of a wheeled transport truck upon which my improved mining machine is adapted to be supported.

Fig. 17 is a plan view of a transport truck of the tracklaying tread type and upon which the machine is adapted to be supported during transport.

Fig. 18 is a diagrammatic view illustrating the different cutting positions of the machine when cutting from right to left.

In the illustrative embodiment of my invention as shown in Figs. 1 to 13, 16, 17, and 18, I have shown a mining machine generally designated 1 which is herein of the flexibly fed room and pillar type slideable on the mine bottom and having a frame 2 of generally rectangular shape presenting parallel plane surfaces 3 and 4 upon which the machine is adapted to be selectively supported, that is, when the machine is being utilized as an undercutter or inverted and utilized as an overcutter. The machine frame 2 comprises a bottom or bed section 5, a motor section 6 disposed at the front end of the machine, and a feed and cutter mechanism carrying section 7, the sections 6 and 7 being supported upon the section 5 and rigidly secured thereto in any approved manner as by screws 8. Moreover, suitably rigidly secured within and projecting forwardly from the bed section 5 is a rigid cutter bar 9 about the outer edges of which a cutter bit carrying cutter chain 10 is adapted to be circulated, the cutter chain being driven through improved transmission means, hereinafter described, from a motor 11, herein of the reversible type, housed within the section 6. As illustrated, a frame section 12 is secured, as by screws 13, to the rear end of the frame section 7 and by this frame section the improved feed operating or controlling members 14 and 15 herein in the form

of chain sprockets, likewise driven from the motor 11, and improved guiding means, hereinafter described, are carried.

In describing my improved cutting mechanism it will herein be observed that the rear end of the longitudinally extending horizontal armature shaft 16 of the motor 11 has secured thereto by means of a key and nut and washer connection 17, a spur motor pinion 18 (see Figs. 7 and 11). The gear 18 is provided with a hub portion 19 journaled within a suitable ball bearing 20 carried within a bore 21 formed within a supporting member or bracket 22 secured, as by suitable screws 23, to the motor frame 6. The member 22 is in turn carried within bores 24 disposed coaxially with the axis of the motor and formed within the frame section 7. It will thus be seen that the member 22 is rigidly secured within the frame section forming an exceedingly stable support for the armature shaft 16. As illustrated the motor pinion 18 is meshed with a spur gear 25 secured, as by a key and screw connection 26, to a longitudinally extending shaft 27 disposed below and parallel with the armature shaft 16. As illustrated, the shaft 27 is journaled within longitudinally spaced ball bearings 28 carried by a bracket 29 rigidly secured, preferably by one of the screws 8, to the bottom of the frame section 7. Furthermore, the shaft 27 has secured, as by a screw connection 30, at its forward end, a bevel pinion 31 which is meshed with a large bevel gear 32 which is in turn secured, as by keys 33 and 34, to the adjacent ends of vertically disposed coaxial shafts 35 and 36. The lower shaft 36 is journaled within suitable vertically spaced ball bearings 37 carried within suitable annular supporting or retaining members 38 and 39 suitably carried by the frame sections 7 and 5, respectively. Moreover, the lower end of the shaft 36 has secured thereto, as by a screw and key connection 40, a spur pinion 41 which is meshed with a large spur gear 42, the hub of which is keyed, as by a key 43, to the lower end of a vertical drive shaft 44, the shaft 44 being disposed in the rear of and parallel with the shafts 35 and 36 in the longitudinal vertical center line of the machine. It will be noted that the spur gears 41 and 42 are disposed within the orbit of the cutter chain 10 contiguous to the bottom of the machine and are housed within a portion of the bed section 5. As illustrated, the shaft 44 is provided with a reduced portion at its lower end which is journaled within a suitable ball bearing 45 carried within a vertical bore 46 formed within an upstanding boss in turn formed upon a removable plate 47 rigidly secured, as by screws 48, to the machine frame, while the upper end of the shaft 44 is disposed within an annular bearing member 49 which is in turn journaled within a ball bearing 50 disposed within a

vertical bore 51 formed within the frame section 7. It will also be observed that an adjustable lock nut 52 is threadedly secured to a reduced threaded portion 53 formed on the shaft 44 and this lock nut permits proper longitudinal positioning of the shaft. A removable cover plate 54 is provided for permitting access to the bearings and shaft and this plate is disposed flush with the surface 4 of the machine frame and is secured to the frame section 7 by means of suitable screws 55. It will further be observed that the hub of the gear 42 is provided with a cylindrical bearing surface 56 on which, and in an annular bearing sleeves 56^a carried by the frame sections 5 and 7, respectively, a cutter chain sprocket 57 of the usual type is journaled and this cutter chain sprocket cooperates with the cutter chain 10 to drive the latter in a well known manner. As illustrated, the cutter chain sprocket 57 is adapted to be connected in operative driving relation with the shaft 44 by means of a clutch shipper member 58 splined, as at 59, to the shaft 44 and which shipper is provided at its lower end with external clutch teeth 60 which are adapted to cooperate with internal clutch teeth 61 formed within the hub of the cutter chain sprocket 57. Furthermore, the shipper member 58 is provided with a circumferential groove 62 with which the arms of a shipper yoke 63 cooperate, the shipper yoke being pivoted, as at 64, on a transverse horizontal axis on an adjustable member 65 threadedly secured within the frame section 12. As illustrated, improved operating and interlocking means are provided for the shipper yoke 63 and this interlocking means comprises an operating rod 66 pivotally connected as at 67 to an upstanding arm 68 formed on the shipper yoke and this rod projects outwardly from the machine frame through an aperture 69 formed within the frame section 12. The outer end of this rod is threadedly secured, as at 70, within a block member 71. Pivotally mounted on the block 71 as by a transverse pin 72 (see Fig. 12) is an operating member 73 provided with parallel arms which straddle a vertically disposed stub shaft 74, the latter forming a support for certain of the guide members for the flexible feeding member, to be hereinafter described. The shaft 74 is non-rotatably secured, as by a key 75, within longitudinally projecting bosses 76 disposed intermediate the feed operating members 14 and 15 and which are formed upon the frame section 12 and this shaft 74 is notched at each side thereof, as at 77 and 78, and is further provided with a transverse slot 79 which connects the notches 77 and 78. It will further be observed that the operating member 73 is provided with inwardly projecting pins 80 which are adapted to selectively lie in the notches 77 and 78. From the foregoing description it

will be evident that when it is desired by the operator to connect the sprocket 57 in operative driving relation with the shaft 44 the operating member 73 is swung upwardly about the pivot 72, thus enabling the pins 80 to be passed through the slot 79 and simultaneously swinging the shipper yoke 63 about its pivot, thus moving the shipper member 58 longitudinally of the shaft and the clutch teeth 60 and 61 in operating relation. When the shipper member is in this position the operating member 73 is then swung downwardly, bringing the pins 80 into engagement with the notch 77, thus locking the shipper member 58 in position. It will also be noted that a similar set of notches are provided in a plane above the slots 79 (see Fig. 11), thus permitting the operating member 73 to be locked in position when the machine is in its inverted position. It will thus be seen that the cutter chain sprocket may be rotated or remain idle at the will of the operator while the motor 11 continuously operates.

In my improved feeding mechanism it will herein be noted that the feed operating members 14 and 15 are adapted to be either independently or simultaneously driven from the motor 11 through improved transmission means, hereinafter described, at a fast or haulage speed and at a slow or cutting speed in the same direction, the feed operating members rotating in opposite relation. In specifically describing the fast feed transmission means it will herein be observed that the shaft 35 is journaled at its upper end within a suitable ball bearing 81 (see Fig. 11) carried within a vertically disposed bore 82 formed within the frame section 7. An adjustable lock nut 83 is also provided, similar to the lock nut 52, for longitudinally positioning the shaft 35. As illustrated, a cover plate 84 secured, as by screws 85 to the frame section 7, is provided to permit free access to the upper end of the shaft 35 and the cooperating parts. Moreover, secured intermediate the ends of the shaft 35, as by a key 86, is a worm 87 which is meshed with worm gears 88 and 89 rotatable in opposite relation on longitudinally extending parallel axes alined with the axes of the feed operating members 14 and 15 respectively and spaced equally at each side of the vertical central longitudinal axis of the machine (see Fig. 7). The worm gears 88 and 89 each have secured thereto, as by studs 90 and 91 respectively, hub portions 92 and 93, the former being journaled within bearing sleeves 94 carried by longitudinally extending horizontal shafts 95 and disposed coaxially with the worm gears 88 and 89. As illustrated, the forward ends of the shafts 95 are journaled within suitable ball bearings 96 carried within suitable retaining members 97 suitably secured within the frame section 7 while the rear ends of the shafts 95 are 130

journaled within ball bearings 98 carried by annular members 99 disposed within circular bores 100 formed within the machine frame and held in non-rotative relation with respect thereto by means of keys 101. Housed within the worm gears 88 and 89 are friction disk clutches, generally designated 102 and 103, which clutches each comprise a series of disks 104 secured within the gears 88 and 89 and which are adapted to cooperate with a series of disks 105 secured with respect to clutch members 106. It will herein be observed that the clutch members 106 are provided with hub portions 107 which are keyed as at 108 to the shafts 95, respectively. Encircling the hubs 93 of the gears 88 and 89 are cylindrical plane clutch operating members 109 which are provided with longitudinally extending fingers 110 which pass through apertures formed in the worm gears and which are adapted to engage certain of the clutch disks 104, 105. As illustrated, the rear ends of the shafts 95 have suitably secured thereto spur pinions 111 which are meshed with a plurality of planetary speed reduction gears 112, which gears are meshed with internal gears 113 formed within the stationary cylindrical members 99. Furthermore, the gears 112 are journaled within suitable ball bearings 114 on longitudinally extending parallel stub shafts 115 carried by planet carrier or spider members 116. As illustrated, these spider members 116 are secured to longitudinally extending shafts 117 disposed coaxially with the shafts 95 at the rear end thereof and these shafts 117 are journaled within longitudinally spaced ball bearings 118 and 119 suitably supported by longitudinally extending cylindrical bosses 120 formed on the frame section 12. It will herein be observed that the shafts 117 are provided with reduced rear end portions 121 which have secured thereto, as by keys 122, the hubs 123 of clutch members 124. Loosely journaled on the hubs 123 are clutch members 125 having secured thereto, as by keys 126, the feed operating members 14 and 15, respectively. It will further be noted that the clutch members 124 and 125 are adapted to be connected in operative driving relation by means of longitudinally reciprocal internal gear clutches 127 disposed coaxially with the shafts 121. From the foregoing it will be evident that when the clutch disks 104, 105 are pressed together in operative driving relation, power is adapted to be transmitted from the motor 11, the armature shaft 16, the motor pinion 18, the spur gear 25 secured to the shaft 27, the bevel pinion 31, the bevel gear 32, the shaft 35, the worm 87, worm gears 88 and 89, clutch members 106 keyed to the shafts 95, pinions 111, planetary gears 112, which react on the stationary internal gears 113, spider members 116, shafts 117, gears 124, clutch members 127, and gears 125, to drive the feed

operating members 14 and 15 in opposite directions at a fast or haulage speed. It will further be noted that by varying the pressure on the friction disks 104 and 105 any suitable variance of such speed may be obtained and by means of the clutch members 127 the feed operating members 14 and 15 may be rotated or remain idle at the will of the operator.

In specifically describing the slow feed transmission means it will herein be observed that secured to the shaft 44 as by a key 130 is a slow speed worm 131 having teeth of less inclination than the teeth of the fast speed worm 87 and which worm 131 is meshed with worm gears 132 and 133, respectively, disposed coaxially with the feed operating members 14 and 15 and the worm gears 88 and 89 and of substantially similar structure. The worm gears 132 and 133 are rotatable in opposite directions and are each provided with hub portions 134 and 135 secured thereto, as by bolts 136, the hub portions 135 being journaled on bearing sleeves 137 carried by the shafts 95 while the hubs 134 are journaled within bearing sleeves 138 carried by the hubs of the clutch members 139 similar to the clutch members 106 and spaced longitudinally with respect thereto by means of suitable annular spacing members carried coaxially with the shafts 95, respectively. The clutch members 139 are keyed, as at 140, to the shafts 95, respectively. Housed within the worm gears 132 and 133 are friction disk clutches, generally designated 141 and 142, substantially similar to the clutches 102 and 103, and which each comprises a series of disks 143 secured with respect to the worm gears and which are adapted to cooperate with a series of disks 144 secured to the clutch members 139. Encircling the hubs 134 of the worm gears are cylindrical plane clutch shipper members 145 having longitudinally extending fingers 146 projecting through suitable apertures formed within the worm gears and which are adapted to cooperate with certain of the series of disks 143 and 144. From the foregoing description it will be evident that when pressure is applied to the disks 143 and 144 and the fast speed clutches 102 and 103 are released, power is adapted to be transmitted from the motor 11 through the armature shaft 16, motor pinion 18, spur gear 25 secured to the shaft 27, bevel pinion 31, bevel gear 32 secured to the shaft 36, spur pinion 41, spur gear 42, shaft 44, worm 131, worm gears 132 and 133, clutch members 139, shafts 95, pinions 111, planetary gears 112 which react on the stationary internal gears 113, and spiders 116 secured to the shafts 117, spur gears 124, clutch members 127, and spur gears 125 to the feed operating members 14 and 15, rotating the same in opposite directions at a slow or cutting speed. It will also be evident that by varying the pressure ap-

plied to the clutch disks 143, 144 any suitable variance of such speed may be obtained at the will of the operator.

Associated with the feed controlling fast and slow speed clutches 102, 141 for the feed operating member 14 and the fast and slow speed clutches 103, 142 for the feed operating member 15 are improved controlling means therefor whereby the clutches may be selectively applied. Such means for each set of clutches comprises shipper yokes 148 and 149 (see Figs. 7, 10, 11 and 13) disposed intermediate the worm gears 88, 132, and 89, 133, respectively, carrying at their upper ends on transverse axes rollers 150 and 151 which are adapted to cooperate with the cylindrical plane clutch shipper members 109, 145, respectively, for each set of clutches and these shipper members are pivoted at their lower ends on traverse pins 152 and 153 carried by hubs 155 and 156 secured to a transversely disposed horizontal shaft 157 and a cylindrical sleeve 158, respectively. As illustrated, the hub 155 has threaded thereto (see Fig. 13) a stud 159 provided with a radially projecting pin 160 which projects through a circumferentially extending slot 161 formed in the sleeve 158 and this pin cooperates with the shaft 157. The slot 151 permits movement of the hub 155 relative to the shaft 157. As shown, the hub 156 has threadedly secured thereto a stud 162 which is provided with a radially extending pin 163 which projects within an aperture 164 formed in the sleeve 158, a groove 165 being provided in the shaft 157, thus permitting rotation between the latter and the sleeve. It will herein be observed that secured to the shaft 157 and the sleeve 158, at the advancing side of the machine, are operating levers 166 and 167, respectively, each of these levers being provided with a spring pressed plunger 168 which is adapted to engage suitable apertures 169 formed in the machine frame, thus permitting the levers and consequently the shipper yokes to be locked in their different adjusted positions. It will further be observed that the hubs 155 and 156 are each provided with plane abutment surfaces 170 and 171 which are adapted to be engaged by projections 172 and 173, respectively, formed on the lower portions of the shipper yokes 148 and 149 and that coiled springs 174 acting between the shipper yokes are provided which are adapted to normally force the abutments 172 and 173 against the surfaces 170 and 171 formed on the hub. From the foregoing description it will be evident that the levers 166 and 167 may be selectively manipulated, thus rotating either the shaft 157 or the sleeve 158 and rotating the hubs, thus causing one or the other of the abutment surfaces 170, 171 to swing one of the yokes 148, 149 away from one of the clutch operating members and the other yoke into engage-

ment with the other clutch operating member, the yoke swinging about its pivot at that time. The spring 174 compresses upon overload of the clutches, thus preventing breakage of the machine parts, for instance, when extremely hard material is encountered during cutting. From the foregoing it will be obvious that the possibility of simultaneous application of the fast and slow speed controlling clutches for each of the members 14 and 15 is entirely eliminated. It will also be noted that a cap member 175 engages the shaft 157 and the sleeve 158 at the opposite end thereof from the levers 166, 167 and this cap is held in position on the shaft by means of a radially expandable split washer 176.

Cooperating with the feed operating members 14 and 15 and the improved guiding means, to be hereinafter described, is a continuous flexible feeding member 180, herein in the form of a feed chain relative to which the machine is adapted to move, and which feeding member presents advance and receding flexible feeding portions 181 and 182 having free ends which are adapted to be connected to fixed extraneous abutments. It will herein be noted that each side of the forward end of the machine frame 2 is provided with rectangular vertically disposed plates 183 secured to the motor section 6 by means of screws 184 and these plates have formed thereon laterally projecting cylindrical bosses 185 (see Fig. 1) upon which swing arms 186 are journaled. The lower end of each of the arms 186 is provided with a cylindrical portion 187 (see Fig. 3) upon which a suitable bearing sleeve 188 is carried forming a journal for an idler sprocket 189, the sprocket being held in position by means of a screw and washer connection 190. As illustrated, projecting laterally from each of the arms 186 is a lug 191 which is adapted to selectively engage abutments 192 and 193 formed upon a circular plate 194. This plate is secured in non-rotative relation with respect to the cylindrical member 185 by means of a clutch and screw connection 195. It will also be observed that disposed at either side of the rear end of the machine frame are guide sheaves 196 each being journaled upon a bearing sleeve 197 (see Fig. 8) carried upon a laterally projecting cylindrical portion 198 formed upon a bracket 199 suitably secured as by a screw 200 and held in non-rotative relation with respect to the machine frame by means of suitable dowel pins 201, screw and washer connections 202 also being provided for preventing lateral displacement of each of the guide sheaves 196. It will herein be noted that at each corner of the rear end of the machine are coaxially disposed sets of guide sheaves 203, 204 and 205, 206 journaled upon vertical parallel shafts 207 and 208, respectively, carried by longitudi-

nally projecting vertically spaced bosses 209, similar to the bosses 76. It will also be noted that journaled at the upper and lower ends of the shaft 74, heretofore described, are coaxially disposed guide sheaves 210 and 211 and these sheaves and the sheaves 203, 204, 205 and 206 are rotatable in horizontal planes substantially tangential to the exterior peripheries of the feed operating members 14 and 15. From the foregoing it will be seen that the advance portion 181 of the feed chain 180 may be extended from the left hand rib of the coal around the front guide sheave 189, carried by the advancing side of the machine, the lug 191 being held against the lower abutment 192, and then rearwardly along the side of the machine over the guide sheave 196, around the lower corner guide sheave 203, upwardly around the feed operating member 14, the slack bight of the chain then passing rearwardly around the upper guide sheave 204 coaxial with the guide sheave 203, and transversely of the machine around the upper corner guide sheave 205, downwardly around the feed operating member 15, and laterally from the rear end of the machine to the right hand rib of the coal when the machine is cutting from right to left. The slack bight of the feed chain is of sufficient length to permit the necessary independence of action of the feed operating members 14 and 15. It will herein be observed that when the machine is cutting from left to right the controlling levers 166 and 167 are transferred to the other side of the machine, as indicated by dotted lines in Fig. 1, the cap member 175 then being removed and transferred to the other end of the shaft 157, the chain reeved relative to the guide sprockets and feed operating members in a reverse manner, the motor 11 being reversed at this time, and the cutter bits reversed in their respective links in the usual manner. If desired, the slack portion of the feed chain may be extended from the upper guide sheave 204 and downwardly between the guide sheaves 210, 211, upwardly around the feed operating member 15, then laterally around the guide sheave 210 and thence rearwardly to the right hand rib, the feed operating member 15 being adapted to pay out the flexible receding portion instead of winding it in during certain of the operations of the machine.

Under certain conditions it is desirable for the cutter bar to operate at a substantial distance above the bottom surface of the mine, for instance, when it is desired to cut out a dirt or slate band between the seams of coal. Under such conditions the machine is enabled without change to be bodily inverted, the upper plane surface 4, as shown in Fig. 2, being disposed upon the mine bottom at that time (see Fig. 5). However, when the machine is disposed in such manner, if desired, the swing arms may be swung about

their journals 185, as indicated by dotted lines in Fig. 5, with the abutment 191 formed thereon engaging the other abutment surface 193 and the screws 200 holding the brackets 199 carrying the sheaves 196 may be released and the bracket 199 swung 180 degrees, as shown in dotted lines in Fig. 5, and the screws are then again tightened. The feed chain 180 is then rereeved relative to the feed operating members 14 and 15 and is extended below the guide sheave 196 and around the front swing arm and laterally thereof to the rib, the feed chain then operating in a plane a substantial distance below the plane of the cutter bar.

Improved means are provided for guiding the machine and bar during its longitudinal sumping movement and for guarding the operator from the rapidly moving cutter bits. This means comprises parallel laterally spaced tubular members 215 which are adapted to project through longitudinally extending openings 216 formed in the bed section 5 below the frame sections 6 and 7. These tubular members 215 have secured thereto, preferably by riveting, laterally projecting lugs 217 which extend within the lower outer corners of the interior of the bed section 5 of the machine frame, thus preventing rotation of the members 215 relative to the frame and forming stops which are adapted to engage longitudinally spaced abutments 218 and 219 formed on the bed frame, thus preventing excessive movement of the members 215 in either direction. The forward ends of the tubular members 215 are provided with inwardly projecting collars 220 preferably brazed thereto which are adapted to be engaged by external collars 221 formed on parallel tubular members 222 which are adapted to telescope within the members 215, the collars 220 thus preventing the withdrawal of the inner members 222 from the outer members 215. As illustrated, the forward ends of the tubular members 222 are connected together by upper and lower transverse cross members 223 and 224, the latter being provided with a curved shoe portion 225 adapted to rest on the mine bottom and thus support the cutter bar. It will herein be noted that these members 223 and 224 are provided with centrally located inwardly projecting guide portions 226 and 227 (see Figs. 1 and 6), respectively, adapted to slide in longitudinally extending grooves 228 and 229 formed in the upper and lower surfaces of the cutter bar 9, thus providing guiding means for the bar. It will further be noted that these tubular members are each open or cut away at their inner sides, as at 230 and 231, respectively, thus permitting the outer edges of the cutter bar to project therein. Moreover, the tubular members 215, 222 form guard members for the cutter chain 10, completely encircling or housing the latter,

thus preventing the operator from coming into contact with the rapidly moving cutter bits when the machine is operating either as an undercutter or an overcutter. It will be evident that the tubular members 215 and 222 may be slid outwardly from the machine frame and extended over substantially the length of the cutter bar when desired, the stop members 217 and 221 preventing separation of the parts. It will further be evident that these tubular members may be telescoped within the machine frame substantially within the longitudinal limits thereof thus forming an exceedingly compact structure.

In the form of my invention shown in Figs. 14 and 15 it will herein be observed that the chain engaging feed operating members or sprockets 14 and 15 have been removed from the shafts 117 and replaced by rope winding drums 235 and 236 upon which suitable wire ropes 237 and 238 are adapted to be wound, these wire ropes forming separate advance and receding feeding portions for the machine. It will also be observed that the guides 189 carried by the front swing arms are replaced by suitable pulleys 239 while the guide sheaves 196 are replaced by suitable pulleys 240. It will further be observed that the sets of chain guide sheaves 203, 204; 205, 206; 210, and 211 disposed on parallel vertical axes at each side of the feed operating members 14 and 15 have been removed and replaced by suitable rope guiding pulleys 241. This form of my machine operates substantially in the same manner as the feed chain form heretofore described with the exception that the slack bight of the flexible feeding member between the feed operating members 181 and 182 is omitted. In each form of my invention it will be observed that there are shown suitable spaces marked Controller and Resistance in which suitable controller and resistance devices (not shown) are disposed.

It will herein be noted that both forms of my machine are adapted to be mounted upon a wheeled transport truck, as shown in Fig. 16, and this truck comprises a truck driving gear 242 rotatable on a longitudinally extending axis and which is adapted to be connected in operative driving relation with either the feed operating member 15 or the feed operating member 236 by means of the 55 sliding clutch member 127 (see Fig. 11), the clutch member 127 being adapted to connect the gear 125 and the gear 242 in operative driving relation, thus enabling the truck driving gear 242 to be driven through the 60 improved fast and slow feed driving connections, heretofore described, from the driving motor 11. Suitable reverse gears 243 are provided which permit the transversely disposed truck driving shaft 244 to be driven in opposite directions at either a fast or a

slow speed under the control of the friction clutches 103, 142. The truck wheels 245 are adapted to be driven from the shaft 244 through suitable chain and sprocket connections 246 and 247, as illustrated. Secured to the shaft 244 is a suitable pulley 248 which is adapted to drive, through a belt connection 249, a pulley 250 secured to the usual electric cable reel 251. My improved mining machines are also adapted to be mounted on a transport truck of the tracklaying tread type and in this case a plurality of truck driving gears 252 and 253 are provided disposed on longitudinally extending parallel axes equally spaced at each side of the center line of the truck frame. These truck driving gears 252 and 253 are adapted to be connected in driving relation with the shafts 117 by means of the slideable clutch members 127 which are adapted to connect the gears 125 and the gears 252 and 253 in operative driving relation. Suitable reversing mechanisms 254 and 255 are provided for each of the truck driving gears, thus permitting the coaxially disposed transverse truck driving shafts 256 and 257 to be independently or simultaneously driven through the improved feeding mechanism at either a fast or a slow speed in opposite directions under the control of the friction clutches 103, 142 and 102, 141.

As illustrated, the tracklaying treads 258 and 259 are of any suitable form and are adapted to be driven from the shafts 256 and 257, respectively, through chain and sprocket connections 260 and 261 in any approved manner. It will further be observed that the truck driving shaft 256 has secured thereto a pulley 263 which is connected through a belt connection 264 in driving relation with a pulley 265 secured to a usual electric cable reel 266. If desired, the cable reel 266 may be driven from the shaft 257 or from both the shafts 256 and 257. From the foregoing it will be seen that when the machine is mounted on the type of truck shown in Fig. 16 the truck wheels 245 may be driven in either direction relative to a trackway directly from the mining machine feeding mechanism at either a fast or a slow speed under the control of the fast and slow speed feed clutches 103, 142 and the reverse mechanism 243 on the truck. While the machine is supported on the type of truck shown in Fig. 17 the tracklaying treads 258 and 259 may be simultaneously or independently driven in opposite directions directly from the mining machine feeding mechanism at either a fast or slow speed under the control of the feed controlling clutches 103, 142 and 102, 141, thus enabling the truck to move forwardly or rearwardly, or when one or the other of the tracklaying treads 258 and 259 is held stationary, to enable the machine to be turned in either direction, in a well known manner.

In the operation of my improved mining

machine it will herein be noted that when the machine is mounted upon its transport truck, power is adapted to be transmitted from the motor 11 through my improved transmission mechanism to the truck wheels to drive the latter at either a fast or slow speed under the control of the feed control clutches. When the machine has been transported into a room from the main entry the clutches 127 are disconnected from the truck drive and slid forwardly, connecting the feed operating members 14 and 15 with the drive shafts 117. One or the other of the flexible feeding portions 181 and 182 is then extended to a stationary abutment or roof jack in advance of the machine and the desired feed controlling clutch is operated rotating the feed operating member at either a fast or a slow speed, thus moving the mining machine from the truck relative to the flexible feeding portion in the usual manner. When the machine is unloaded from the truck the machine is advanced to the face adjacent the right hand rib, when the machine is cutting from right to left as shown in full lines in Fig. 18, at the desired speed likewise under the control of the feed operating members 14 or 15. The receding flexible portion 182 is then connected adjacent the right hand rib of the coal to a jack or take-up device A, while the advancing portion 181 is extended laterally from the front guide sheave 189 of the machine at the advancing side of the machine to a jack or take-up device B disposed adjacent the face at the left hand rib of the coal. The cutter chain sprocket 57 is then connected in driving relation with the motor 11 by means of the clutch 60, 61, thus causing the cutter chain to be rapidly circulated about the cutter bar 9. The clutch 142 controlling the slow speed drive to the feed operating member 15 is then applied and the machine is fed relative to the flexible portion 182 and the bar fed or sumped into the face of the coal at a slow or cutting speed, the friction clutch 141 controlling the slow speed drive for the feed operating member 14, maintaining the desired controlling tension on the advance feeding portion 181 at that time. It will be evident that the sumping speed may be lowered at will by slipping the slow speed friction clutch 142. It will herein be noted that in extremely soft cutting, the bar may be sumped or fed into the coal by means of the fast speed friction 103. It will further be noted that if desired both of the flexible portions 181, 182 may be secured at the face of the coal by suitable roof jacks and the machine fed relative thereto by means of the members 14 and 15 at the desired cutting speed. As the cutter bar is sumped into the coal the tubular members 215 and 222, which normally extend outwardly over the cutter bar, telescope within the machine frame. After the sumping cut has been made

the friction clutch member 141 controlling the slow speed drive for the feed operating member 14 is applied causing the latter to move the machine relative to the advanced flexible portion 181, thus causing the forward end of the machine to swing laterally and bringing the cutter bar to a point substantially perpendicular to the face of the coal. The machine is then fed transversely across the face relative to the advanced portion 181 at a slow or cutting speed by means of the feed operating member 14 under control of the slow speed clutch 141, the desired controlling tension being maintained on the receding flexible portion 182 at that time by means of the slow speed clutch 142 controlling the rotation of the feed operating member 15, the latter constantly tending to draw in the receding portion 182 at a slow speed. By maintaining such tension on the receding portion 182 the rear end of the machine is prevented from moving forwardly, swinging the bar out from the coal. If it is desired to angle the machine during the transverse cut, for instance if extremely hard material is encountered by the cutter bits, the rotation of the feed operating member 14 may be decreased under the control of the slow speed friction clutch 141 while the speed of the rotation of the feed operating member 15 may be increased by the application of the fast speed clutch 103 and the rear end of the machine is then swung rearwardly until the cutter bar is at the desired inclination relative to the coal face. If it is desired to swing the machine in the opposite direction the tension on the receding flexible portion 182 is decreased by release of the slow speed friction 142, the pull on the advancing portion 181 and the reaction of the cutter bits against the coal causing the rear end of the machine to swing forwardly until the bar is at the desired angle. At the end of the transverse cut the speed of rotation of the feed operating member 14 is decreased by suitable release of the slow speed clutch 141 and the speed of rotation of the feed operating member 15 is increased by suitable application of the fast speed clutch 103, thus causing the bar to be slightly angled as indicated by dotted lines in Fig. 18. A suitable roof jack is then placed against the transverse member 223 of the sumping guide and the advanced flexible portion 181 is then extended rearwardly from the guide sheave 196 on the advancing side of the machine to the rear of the machine and the free end thereof is secured by means of the roof jack B, the latter being removed from the face at that time. The slow speed clutch 141 controlling the feed operating member 14 is then applied moving the machine relative to the advance portion 181 and the cutter bar is withdrawn from the coal at the desired cutting speed, the tubular members 215 and 222 sliding from the ma-

chine frame during that operation. The cutter chain sprocket controlling clutch 60, 61 is then thrown out and one or the other of the flexible feeding portions 181 and 182 is connected to a stationary abutment or jack adjacent the transport truck and the machine is then fed across the mine bottom at a fast or haulage speed under the control of one or the other of the fast speed clutches 102, 103, the machine then being loaded upon the transport truck in the usual manner. When the machine is cutting from left to right the operation is substantially the same, with the exception that the receding feeding portion 182 is then used as the advance portion and the advance portion 181 is then used as the receding portion, the motor 11 being reversed, the feed chain suitably rereved relative to the feed operating members 14 and 15 and the guides, and the cutter bits reversed in their respective links.

The operation of the wire rope form of the machine shown in Figs. 14 and 15 is substantially the same as the chain form heretofore described with the exception that a plurality of separate feeding portions or ropes are utilized instead of the continuous feeding portion and these ropes are wound upon the drums 235 and 236, respectively. The operation of both forms of my machine when utilized as an overcutter is substantially the same as the operation of the machine when used as an undercutter, with the exception that the machine is bodily inverted with the cutter bar at a substantial distance above the mine bottom. It will herein be noted that during the various operations of the machine disclosed, excessive strain or load upon the feed operating members 14 and 15 is obviated by means of the coiled springs 174 between the shipper yokes for each set of the clutches 102, 141 and 103, 142, respectively, the springs compressing or yielding upon such overload. Various other operations of the machine by means of my invention will be clearly apparent to those skilled in the art.

As a result of my invention it will herein be noted that an improved mining machine is provided which is operable to cut in opposite directions having improved flexible feeding and controlling means therefor. It will further be noted that an improved mining machine is provided having an improved arrangement of the transmission means and the feed operating members whereby the machine may be controlled and fed with facility and having improved truck driving connections. It will also be noted that an improved mining machine is provided of exceedingly compact rugged character especially adapted to use in low vein work having improved and simplified cutting and feeding mechanism. It will still further be noted that improved guiding means for the machine and guarding means for the cutter bar is pro-

vided which is operative whether the machine is operating as an undercutter or an overcutter. It will also be noted that the machine is substantially symmetrical on each side of the longitudinal center line thereof, thus producing a well balanced mechanism. Other advantages of my improved mining machine will be clearly apparent to those skilled in the art.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a driving motor, and feeding means driven from the rear end thereof including a feed operating member rotatable on an axis extending longitudinally of the machine and adapted to cooperate directly with flexible feeding means, and power transmission means connected with said feed operating member including a worm gear disposed coaxially with said member.

2. In a mining machine, a driving motor, and feeding means driven from the rear end thereof including a feed operating member rotatable on an axis extending longitudinally of the machine and adapted to cooperate directly with flexible feeding means, and power transmission means connected with said feed operating member including a plurality of worm gears disposed coaxially with said member and selectively operable to drive said member.

3. In a mining machine, a driving motor, and feeding means driven thereby including feed operating members rotatable on parallel axes and adapted to cooperate with flexible feeding means and driving and controlling means therefor including a friction clutch disposed coaxially with each of said members.

4. In a mining machine, a driving motor, and feeding means driven thereby including feed operating members rotatable on parallel axes and adapted to cooperate with flexible feeding means and driving and controlling means therefor including a plurality of friction clutches disposed coaxially with each of said members.

5. In a mining machine, a driving motor, a plurality of feed operating members adapted to cooperate directly with flexible feeding means and rotatable on parallel axes, and transmission means between said motor and each of said feed operating members including a plurality of speed controlling clutches individual to each feed operating member.

6. In a mining machine, a driving motor,

a plurality of feed operating members rotatable on parallel axes and each adapted to cooperate directly with flexible feeding means, and transmission means between said motor and said feed operating members including a friction clutch disposed coaxially with each of said members.

7. In a mining machine, a driving motor, a plurality of feed operating members rotatable on parallel longitudinally extending axes and each adapted to cooperate directly with flexible feeding means, and transmission means between said motor and said members including a worm gear disposed coaxially with and individual to each of said members.

8. In a mining machine, a driving motor, a plurality of feed operating members rotatable on parallel longitudinally extending axes and adapted to cooperate directly with flexible feeding means, and transmission means between said motor and said members including a plurality of worm gears disposed coaxially with and individual to each of said members.

9. In a mining machine, a driving motor, a plurality of feed operating members rotatable on axes extending longitudinally of the machine and each adapted to cooperate directly with flexible feeding means, and transmission means between said motor and said members including a plurality of friction clutches.

10. In a mining machine, a driving motor, a plurality of feed operating members rotatable on axes extending longitudinally of the machine and each adapted to cooperate directly with flexible feeding means, and variable speed transmission means between said motor and each of said members including a friction clutch.

11. In a mining machine, a driving motor, a plurality of feed operating members each adapted to cooperate directly with flexible feeding means and rotatable on parallel axes, and transmission means between said motor and said members including a plurality of worms rotatable on vertical axes between the axes of said members.

12. The combination with a mining machine, of feeding means therefor including parallel feed operating members adapted to cooperate with flexible feeding means, and actuating means therefor including a plurality of worms disposed vertically between the parallel axes of said members and rotating at different speeds.

13. The combination with a mining machine, of feeding means therefor including parallel feed operating members adapted to cooperate with flexible feeding means, and fast and slow speed actuating means therefor including a plurality of worms disposed vertically between the parallel axes of said members.

14. The combination with a mining ma-

chine, of feeding means therefor including parallel feed operating members adapted to cooperate with flexible feeding means, and actuating means therefor including a plurality of worms disposed vertically between the parallel axes of said members and common to both of said members.

15. The combination with a mining machine, of feeding mechanism therefor including substantially parallel feed operating members rotatable on axes extending longitudinally of the machine and adapted to cooperate with flexible feeding means, and fast and slow speed actuating means therefor including driving mechanism disposed substantially in a zone between the parallel axes of said members.

16. In a mining machine having substantially parallel feed operating members adapted to cooperate with flexible feeding means and rotatable on axes extending longitudinally of the machine, cutting mechanism, and actuating means for said members including a plurality of substantially vertical shafts, driving connections between said shafts and said members including a plurality of worms carried by said shafts, respectively.

17. In a mining machine having substantially parallel feed operating members adapted to cooperate with flexible feeding means and rotatable on axes extending longitudinally of the machine, cutting mechanism, and fast and slow speed actuating means for said members including a plurality of substantially vertical shafts, and driving connections between said shafts and said members including a plurality of worms carried by said shafts, respectively.

18. A mining machine having feeding means therefor including a plurality of feed operating members adapted to cooperate directly with flexible feeding means and rotatable on substantially longitudinally extending axes, and actuating means for said members including a plurality of shafts disposed coaxially with said members, and a shaft common to each of said other shafts for driving the latter and angularly disposed relative thereto in a position between the latter.

19. In a mining machine, a feed operating member adapted to cooperate directly with flexible feeding means and rotatable about an axis extending longitudinally of the machine, and driving means for said member including a shaft disposed coaxially with said axis, a second shaft disposed transversely of and laterally offset from said axis, and gears mounted directly on each of said shafts and meshing with each other.

20. In a mining machine, a horizontal motor extending longitudinally of the machine, and feeding mechanism including relatively rotatable flexible feeding member winding members disposed on axes parallel with that of said motor, and driving mecha-

- nism between the rear end of said motor and said members including a friction clutch disposed coaxially with one of the latter.
21. In a mining machine, a motor and feeding mechanism including relatively rotatable flexible feeding member winding members disposed on parallel axes parallel with that of said motor, and driving mechanism between said motor and said members including a friction clutch disposed coaxially with each of the latter. 70
22. In a mining machine, a motor and feeding mechanism including relatively rotatable flexible feeding member winding members disposed on parallel axes parallel with that of said motor, and driving mechanism between said motor and said members including a plurality of friction clutches disposed coaxially with one of the latter. 75
23. In a mining machine, a motor and feeding mechanism including relatively rotatable flexible feeding member winding members disposed on parallel axes parallel with that of said motor, and driving mechanism between said motor and said members including a plurality of friction clutches disposed coaxially with each of the latter. 80
24. In a mining machine, a motor, a feed-operating member rotatable on an axis extending longitudinally of the machine and adapted to cooperate directly with flexible feeding means, and transmission means between said motor and said member including a plurality of worms selectively operating able to rotate said member. 85
25. In a mining machine, a motor, a feed-operating member rotatable on an axis extending longitudinally of the machine and adapted to cooperate directly with flexible feeding means, and transmission means between said motor and said member including a plurality of worms rotatable on vertical axes. 90
26. In a mining machine, a motor, a feed-operating member rotatable on an axis extending longitudinally of the machine and adapted to cooperate directly with flexible feeding means, and transmission means between said motor and said feed operating member including a plurality of worm gears disposed coaxially with the latter. 95
27. In a mining machine, a motor, a feed-operating member rotatable on an axis extending longitudinally of the machine and adapted to cooperate directly with flexible feeding means, and transmission means between said motor and said feed operating member including a plurality of worm gears, a transmission shaft disposed coaxially with said member, and friction clutches for selectively connecting said gears with said shaft. 100
28. The combination with a mining machine, of feeding means therefor including a plurality of feed operating members rotatable on parallel axes extending longitudinally of the machine and each adapted to cooperate with flexible feeding means, and driving and controlling means for said members including a sliding clutch disposed coaxially with each of said members and a common driving motor for said members. 105
29. In a mining machine, a motor, a plurality of feed sprockets rotatable on parallel axes extending longitudinally of the machine and adapted to cooperate with a flexible feed chain, transmission means between said motor and said sprockets, and independent controlling means for said sprockets. 110
30. In a mining machine, a motor, a plurality of feed sprockets rotatable on parallel axes extending longitudinally of the machine and adapted to cooperate with a flexible feed chain, fast and slow speed transmission means between said motor and said sprockets, and independent controlling means for said sprockets. 115
31. In a mining machine, a motor, a plurality of feed operating members rotatable on parallel axes extending longitudinally of the machine and each adapted to cooperate directly with flexible feeding means, and transmission means between one of said members and said motor including planetary gearing arranged coaxially with the latter member. 120
32. In a mining machine, a motor, a plurality of feed operating members rotatable on parallel axes extending longitudinally of the machine and adapted to cooperate directly with flexible feeding means, and transmission means between said motor and one of said members including worms rotatable on parallel vertical axes, and a plurality of worm gears meshing therewith rotatable on axes coaxial with said feed operating members. 125
33. In a mining machine, a motor, a plurality of feed operating members rotatable on parallel axes extending longitudinally of the machine and adapted to cooperate directly with flexible feeding means, and transmission means between said motor and each of said members including worms rotatable on parallel vertical axes, and a plurality of worm gears meshing therewith rotatable on axes coaxial with said feed operating members. 130
34. In a mining machine, a motor, a plurality of feed operating members rotatable on parallel axes extending longitudinally of the machine and adapted to cooperate directly with flexible feeding means, and transmission means between said motor and one of said members including worms rotatable on parallel vertical axes, a plurality of worm gears meshing therewith rotatable on axes coaxial with said feed operating members, a transmission shaft, and friction clutches for 135

selectively connecting said gears with said shaft.

35. In a mining machine, a motor, a plurality of feed operating members rotatable on parallel axes extending longitudinally of the machine and adapted to cooperate directly with flexible feeding means, and transmission means between said motor and each of said members including a plurality of worms rotatable on parallel vertical axes, a plurality of worm gears meshing therewith one disposed coaxially with each of said members, transmission shafts, and friction clutches for selectively connecting said gears with said shafts.

36. The combination with a mining machine of the type which is slidable on the mine bottom during cutting, of feeding and guiding means therefor including independently operable feed operating members rotatable on parallel axes and adapted to cooperate with flexible feeding means, and guiding means for the flexible feeding means disposed intermediate said members.

37. The combination with a mining machine, of feeding means therefor including independently operable feed operating members rotatable on parallel axes and adapted to cooperate with flexible feeding means, and guiding means for said flexible feeding means including coaxial guide sheaves disposed intermediate said feed operating members.

38. The combination with a mining machine, of feeding means therefor including feed operating members rotatable on parallel axes and adapted to cooperate with flexible feeding means, and guiding means for said flexible feeding means including coaxial guide sheaves disposed at each side of said feed operating members.

39. The combination with a mining machine, of feeding means therefor including feed operating members rotatable on parallel axes extending longitudinally of the machine and adapted to cooperate with flexible feeding means, and guiding means for said flexible feeding means including coaxial guide sheaves disposed at each side of and intermediate said feed operating members.

40. The combination with a mining machine, of feeding means therefor including feed operating members rotatable on parallel axes extending longitudinally of the machine and adapted to cooperate with flexible feeding means, and guiding means for said flexible feeding means including coaxial guide sheaves disposed at each side of and intermediate said feed operating members and rotatable in planes above and below the axes of the latter.

41. In a mining machine, a motor, a plurality of feed operating members rotatable on parallel axes and each adapted to cooperate directly with flexible feeding means, and transmission means between said motor and

said feed operating members including a worm rotatable on a vertical axis, and planetary gearing disposed coaxially with said members.

42. In a mining machine, a motor, a plurality of independently operable feed operating members driven thereby rotatable on parallel axes extending longitudinally of the machine and each adapted to cooperate directly with flexible feeding means, and transmission means between said motor and each of said members including a plurality of gears disposed coaxially therewith, and friction clutches.

43. In a mining machine, a motor, a plurality of feed operating members driven thereby rotatable on parallel axes extending longitudinally of the machine and each adapted to cooperate directly with flexible feeding means, and transmission means between said motor and each of said members including a plurality of gears disposed coaxially therewith, and selectively operative friction clutches.

44. The combination with a mining machine, feeding means therefor including a feed operating member adapted to cooperate directly with flexible feeding means, a plurality of friction clutches disposed coaxially therewith, and means for selectively applying said clutches including a plurality of pivoted shipper yokes and a spring acting between said yokes.

45. In a mining machine, a motor, and a plurality of feed operating members driven thereby rotatable on parallel axes extending longitudinally of the machine and adapted to cooperate directly with flexible feeding means, and means for controlling said members including friction clutches disposed coaxially therewith.

46. A mining machine slidable on its bottom on a mine bottom, a motor, a cutter chain driven thereby, and transmission means between said motor and said cutter chain including gearing rotatable in planes above and below the plane of said cutter chain.

47. A mining machine slidable on its bottom on the mine bottom, a motor, a cutter chain driven thereby including a drive sprocket, and transmission means between said motor and said cutter chain including gearing disposed in a plane above said cutter chain and a gear disposed coaxially with and below the drive sprocket.

48. The combination with a mining machine comprising a longitudinally movable cutter bar about which a cutter chain is adapted to be circulated, of a guard device for the cutter chain comprising laterally spaced parallel longitudinally extending tubular members connected together at one end and through which said cutter chain is adapted to pass.

49. The combination with an invertible

mining machine having a frame presenting parallel plane surfaces upon which the same is adapted to be selectively supported, and a cutter bar extending longitudinally from said frame about which a cutter chain is adapted to be circulated, of shrouding means to guard the cutters of said chain when the machine is supported upon either plane surface.

50. The combination with a mining machine comprising a longitudinally movable cutter bar about which a cutter chain is adapted to be circulated, said bar being provided with parallel longitudinally extending grooves, of a guard device for said cutter chain comprising parallel longitudinally extending tubular members connected together at one end through which the cutter chain is adapted to pass, said members being guided in the grooves in said bar.

51. The combination with a mining machine comprising a longitudinally movable cutter bar about which a cutter chain is adapted to be circulated, of a guard device for said cutter chain comprising laterally spaced parallel longitudinally extending tubular members connected together at one end, said members being open at one side to permit the cutter chain to advance therethrough.

52. The combination with a mining machine having a frame presenting parallel plane surfaces upon which the same is adapted to be selectively supported and a cutter bar extending longitudinally from said frame about which a cutter chain is adapted to circulate, of means to guard the cutter chain when the machine is supported upon either plane surface, said means comprising parallel longitudinally extending tubular members through which the cutter chain passes.

53. The combination with a mining machine comprising a longitudinally movable cutter bar about which a cutter chain is adapted to be circulated, of a guard device for said cutter chain comprising parallel longitudinally extending telescopedically arranged tubular members, certain of said members being connected together at one end and through which the cutter chain passes.

54. In a mining machine of the type slideable on its bottom over a mine bottom during cutting, machine guiding and feeding mechanism including flexible feeding means including a plurality of flexible feeding portions, a plurality of alternatively operative worms of different pitch operatively connected with one another by intermeshing spur gears, and a plurality of feed operating members rotatable upon parallel axes cooperating respectively with said flexible portions and selectively connectible in driving relation with said worms.

55. In a mining machine, feeding mecha-

nism including flexible feeding means including a plurality of flexible feeding portions, a plurality of alternatively operative worms of different pitch operatively connected with one another by intermeshing spur gears, and a plurality of feed operating members rotatable upon parallel axes extending longitudinally of the machine cooperating, respectively, with said flexible portions and selectively connectible with said worms.

56. In a mining machine of the type slideable on its bottom over a mine bottom during cutting, machine guiding and feeding mechanism including flexible feeding means including a plurality of flexible feeding portions, a plurality of alternatively operative worms of different pitch operatively connected with one another by intermeshing spur gears, and a plurality of feed operating members cooperating respectively with said flexible portions and selectively connectible with said worms, said feed operating members being arranged for rotation on parallel axes.

57. In a mining machine, feeding mechanism including flexible feeding means including a plurality of flexible feeding portions, a plurality of alternatively operative worms of different pitch operatively connected with one another by intermeshing spur gears, and a plurality of feed operating members cooperating respectively with said flexible portions and selectively connectible with said worms, said feed operating members being arranged for rotation upon parallel longitudinally extending axes.

58. In a mining machine of the type slideable on its bottom over a mine bottom during cutting, machine feeding and guiding mechanism including flexible feeding means including a plurality of flexible feeding portions, a plurality of worms rotatable on parallel axes and operative as feed driving members, and a plurality of feed operating members rotatable on parallel axes cooperating respectively with said feeding portions and connectible with said worms.

59. In a mining machine, feeding mechanism including flexible feeding means including a plurality of flexible feeding portions, a feed operating member rotatable on an axis extending longitudinally of the machine cooperating with one of said flexible feeding portions, and driving mechanism for said feed operating member including a plurality of spiral gears of different pitch alternatively operative as driving members, cooperating spiral gears driven thereby, and a plurality of clutches which determine which spiral gear shall constitute the driving element.

60. In a mining machine, feeding mechanism including flexible means providing a plurality of flexible feeding portions, feed operating members rotatable on parallel axes cooperating with each of said portions, and driving mechanism for each of said feed oper-

ating members including a plurality of spiral gears of different pitch alternatively operative as drive members, cooperating spiral gears driven by said first mentioned spiral gears, a shaft coaxial with said cooperating spiral gears, disc clutches for each of said cooperating gears controlling the connection of said gears to said shaft, and operative connections between said shaft and the feed operating member driven thereby including separate clutches between said shaft and each of said members.

61. In a mining machine, feeding mechanism including flexible feeding means providing a plurality of flexible feeding portions, feed operating members rotatable upon parallel axes extending longitudinally of the machine cooperating with each of said portions, and driving mechanisms for each of said feed operating members including a plurality of spiral gears of different pitch alternatively operative as drive members, cooperating spiral gears driven by said first mentioned spiral gears, a shaft coaxial with said cooperating spiral gears, a disc clutch for each cooperating gear controlling the connection of said gear to said shaft, and operative connections between said shaft and said feed operating members including separate clutches between said shaft and each of said members, each feed operating member and all of said clutches through which it is driven being coaxial with its respective shaft.

62. In a mining machine, a motor, feed operating members rotatable in the same vertical transverse plane on axes extending longitudinally of the machine and each adapted to cooperate directly with flexible feeding means, cutting mechanism, transmission means between said motor and said feed operating members, and means for driving said cutting mechanism from said transmission means which drives said feed operating members.

63. In a mining machine, a motor, feed operating members rotatable in the same transverse plane on parallel axes extending longitudinally of the machine and each adapted to cooperate with flexible feeding means, and transmission means between said motor and said feed operating members including a plurality of worm gears disposed coaxially therewith.

64. In a mining machine, a motor, feed operating members rotatable in the same transverse plane on parallel axes extending longitudinally of the machine and each adapted to cooperate with flexible feeding means, and transmission means between said motor and said feed operating members including a plurality of friction clutches disposed coaxially therewith.

65. In a mining machine, a driving motor, feeding means driven thereby including feed

operating members rotatable in the same transverse plane on parallel axes and adapted to cooperate with flexible feeding means, and a friction clutch disposed coaxially with each of said members.

66. In a mining machine, a motor, cutting mechanism actuated thereby, and feeding means driven by said motor including feed operating members rotatable on parallel axes and each adapted to cooperate with flexible feeding means, and transmission means between said motor and said cutting mechanism including a clutch, and operating means for said clutch disposed between the axes of said feed operating members.

67. A mining machine comprising a frame presenting parallel plane surfaces upon which the machine is adapted to be selectively supported during cutting, and feeding means for said machine operable while supported on either surface including feed operating members rotatable on parallel axes and each adapted to cooperate with flexible feeding means.

68. A mining machine comprising a frame presenting parallel plane surfaces upon which the machine is adapted to be selectively supported during cutting, and feeding means for said machine operable while supported on either surface including feed operating members rotatable on parallel horizontal axes extending longitudinally of the machine.

69. A mining machine comprising a frame presenting parallel plane surfaces upon which the machine is adapted to be selectively supported during cutting, and feeding means for said machine operable while supported on either surface including feed operating members rotatable on parallel axes in the same transverse plane and each adapted to cooperate with flexible feeding means.

70. A mining machine comprising a frame presenting parallel plane surfaces upon which the machine is adapted to be selectively supported during cutting, and feeding means for said machine while supported on either surface including feed operating members rotatable on parallel axes at the rear end of said machine and each adapted to cooperate with flexible feeding means.

71. In a mining machine adapted to be supported on a truck, means for driving the truck from said machine including independently operable driving elements rotatable on parallel axes extending longitudinally of the machine and either rotatable to effect drive while the other is stationary.

72. In a mining machine adapted to be supported on a truck, means for driving the truck from said machine including independently operable driving elements rotatable on parallel axes extending longitudinally of the machine, and driving and controlling means for

said elements including clutches disposed coaxially therewith.

73. In a mining machine adapted to be supported on a truck, means for driving the truck from said machine including independently operable driving elements rotatable on parallel axes extending longitudinally of the machine, and driving and controlling means for said elements including sliding clutches disposed coaxially therewith.

74. In a mining apparatus, a mining machine slideable on the mine bottom during cutting, a truck adapted to support the machine for transport including independently operable truck driving elements rotatable on parallel axes, and means whereby said elements may be driven from said machine.

75. In a mining machine, feeding mechanism including feed operating members rotatable on parallel axes extending longitudinally of the machine, each adapted to cooperate directly with flexible feeding means, a truck adapted to support said machine having a truck driving element adapted to be disposed coaxially with one of said feed operating members, and means whereby said truck driving element may be driven from said machine.

76. In a mining machine, feeding mechanism including feed operating members rotatable on parallel axes extending longitudinally of the machine, each adapted to cooperate directly with flexible feeding means, a truck adapted to support said machine having truck driving elements rotatable on parallel axes, and means whereby said feed operating members and said truck driving elements may be selectively driven from said feeding mechanism.

77. In a mining machine, the combination of a motor, a pair of feed operating shafts mounted for rotation on parallel axes extending longitudinally of the machine, and power transmitting means between said motor and shafts comprising a pair of vertically disposed shafts positioned between said feed operating shafts and respectively geared thereto at different speed ratios, and means for transmitting the drive through either vertical shaft.

78. In a mining machine, a horizontal driving motor having its axis extending longitudinally of the machine, and feeding means driven thereby including a feed operating member rotatable on an axis extending longitudinally of the machine and adapted to cooperate directly with a flexible feeding member, and a worm driving gear disposed coaxially therewith.

79. In a mining machine, a horizontal driving motor having its axis extending longitudinally of the machine, and feeding means driven thereby including a feed operating member rotatable on an axis extending longi-

tudinally of the machine and adapted to cooperate directly with a flexible feeding member, and a plurality of worm gears disposed coaxially therewith and selectively operable to drive said member.

80. In a mining machine, a driving motor, and feeding means driven thereby including a feed operating member rotatable on an axis extending longitudinally of the machine and adapted to cooperate directly with a flexible feeding member, and a plurality of worm gears disposed coaxially therewith and selectively operable to drive said member.

81. In a mining machine, a driving motor, and feeding means driven thereby including a feed operating member rotatable on an axis extending longitudinally of the machine and adapted to cooperate directly with a flexible feeding member, and a plurality of worm gears disposed coaxially therewith and selectively operable to drive said member at different predetermined speeds.

82. In a mining machine, a driving motor, and feeding means driven thereby including a feed operating member rotatable on an axis extending longitudinally of the machine and adapted to cooperate directly with a flexible feeding member, a plurality of worm gears disposed coaxially therewith and selectively operable to drive said member at different predetermined speeds, and means for varying said speeds.

83. In a mining machine, a feed operating member rotatable about an axis extending longitudinally of the machine and adapted to cooperate directly with a flexible feeding member, driving means therefor including a motor, a shaft disposed coaxially with said member, a second shaft disposed transversely of said axis, gears mounted directly on each of said shafts and meshing with each other, and means for rotating said coaxial shaft in opposite directions without reversing said motor.

84. In a mining machine, a feed operating member rotatable about an axis extending longitudinally of the machine and adapted to cooperate directly with a flexible feeding member, driving means therefor including a motor, a shaft disposed coaxially with said member, a second shaft disposed transversely of said axis, gears mounted directly on each of said shafts and meshing with each other, and means for rotating one of said shafts in opposite directions without reversing said motor.

85. In a mining machine, a feed operating member rotatable about an axis extending longitudinally of the machine and adapted to cooperate directly with a flexible feeding member, driving means therefor including a motor, a shaft disposed coaxially with said member, a second shaft disposed transversely of said axis, gears mounted directly on each of said shafts and meshing with each other,

and means for rotating one of said shafts at different speeds in opposite directions without reversing said motor.

86. In a mining machine, a feed operating member rotatable about an axis extending longitudinally of the machine and adapted to cooperate directly with a flexible feeding member, driving means therefor including a motor, a shaft disposed coaxially with said member, a second shaft disposed transversely of said axis, gears mounted directly on each of said shafts and meshing with each other, and means for rotating said coaxial shaft at different speeds in opposite directions without reversing said motor.

87. In a mining machine, a motor, feeding means including a plurality of feed sprockets rotatable on parallel axes extending longitudinally of the machine and perpendicular to the working face, a flexible feed chain cooperating with said sprockets, and transmission means between said motor and said sprockets whereby the same may rotate simultaneously at different speeds.

88. In a mining machine, a motor, feeding means including a plurality of feed sprockets rotatable on parallel axes extending longitudinally of the machine and perpendicular to the working face, a flexible feed chain cooperating with said sprockets, and fast and slow speed transmission means between said motor and said sprockets whereby the latter may be simultaneously rotated at different speeds.

89. In a mining machine, a motor, feeding means including a plurality of feed sprockets rotatable on parallel axes extending longitudinally of the machine and perpendicular to the working face, a flexible feeding chain cooperating with said sprockets, and fast and slow speed transmission means between said motor and said sprockets whereby the latter may independently act on said feed chain.

90. In a mining machine, a motor, feeding means including a plurality of feed sprockets rotatable on parallel axes extending longitudinally of the machine and perpendicular to the working face, a flexible feeding chain cooperating with said sprockets, and fast and slow speed transmission means between said motor and said sprockets whereby the latter may independently act on said feed chain and may independently draw in different portions of said chain.

91. A mining machine slidable on its bottom on the mine bottom, a horizontal motor, a cutter chain driven thereby and disposed in a plane below said motor, and transmission means between said motor and said cutter chain including gearing rotatable in a plane below the plane of said cutter chain.

92. In a mining machine slidable on its bottom on the mine bottom, a horizontal motor, a cutter chain driven thereby and dis-

posed in a plane below said motor including a drive sprocket, and transmission means between said motor and said cutter chain including a gear disposed coaxially with and below said sprocket.

93. The combination with a mining machine, of feeding means therefor including feed operating members rotatable on parallel axes and adapted to cooperate with flexible feeding means, and guiding means for said flexible feeding means including coaxial guide sheaves disposed intermediate said members, one of said sheaves being disposed in a plane tangential with the upper surfaces of said members.

94. The combination with a mining machine, of feeding means therefor including feed operating members rotatable on parallel axes and adapted to cooperate with flexible feeding means, and guiding means for said flexible feeding means including coaxial guide sheaves disposed intermediate said members, one of said sheaves being disposed in a plane tangential with the upper surfaces of said members while the other sheave is disposed in a plane tangential with the bottom surfaces thereof.

95. In a mining machine, a driving motor, and feeding means driven thereby including independently operable feed operating members rotatable on parallel axes and adapted to cooperate with flexible feeding means, and a plurality of speed controlling clutches a plurality of which are disposed coaxially with each of said members.

96. In a mining machine, a driving motor, and feeding means driven thereby including feed operating members rotatable on parallel axes and adapted to cooperate with flexible feeding means, and a plurality of speed controlling clutches a plurality of which are individual to each member for independently controlling each of said members.

97. In a mining machine, a driving motor, and feeding means driven thereby including feed operating members rotatable on parallel axes extending longitudinally of the machine and adapted to cooperate with flexible feeding means, and a plurality of speed controlling clutches a plurality of which are individual to each member for independently controlling each of said members.

98. In a mining machine, a driving motor, and feeding means driven thereby including independently operable feed operating members rotatable on parallel axes and adapted to cooperate with flexible feeding means, and friction speed controlling clutches disposed one coaxial with each of said members.

99. In a mining machine, a driving motor, and feeding means driven thereby including independently operable feed operating members rotatable on parallel axes extending longitudinally of the machine, and a single con-

tinuous flexible element cooperating directly with both of said members simultaneously.

100. In a mining machine, a driving motor, and feeding means driven thereby including independently operable feed operating members rotatable on parallel axes extending longitudinally of the machine, and a single continuous flexible element cooperating directly with both of said members simultaneously, 5 said members being adapted to draw in different portions of said element.

101. In a mining machine of the invertible type having a machine frame presenting parallel plane supporting surfaces upon 15 which the machine is adapted to be selectively supported, feeding means for the machine including a feed operating member having its axis lying in a vertical plane extending longitudinally of the machine and a flexible feeding element cooperating therewith, and guiding means for said flexible element including a swingable guiding element operative to direct said flexible element from adjacent the bottom surface of the machine when the latter 20 is supported in either of its inverted positions.

102. In a mining machine, a frame slidable on its bottom on the mine bottom, feeding means for the machine including a feed operating member rotatable on an axis lying in a 25 vertical plane extending longitudinally of the machine and a cooperating flexible feeding element, and guiding means for said element including a swingable guiding member disposable by swinging movement adjacent either the top or bottom surface of said frame and adapted to guide the flexible feeding element in either of said positions.

103. In a mining machine, a frame slidable 30 on its bottom on the mine bottom, feeding means for the machine including a feed operating member rotatable on an axis lying in a vertical plane extending longitudinally of the machine and a cooperating flexible feeding element, and guiding means for said element including a swingable guiding member disposable by swinging movement adjacent either the top or bottom surface of said frame and adapted to guide the flexible feeding element in either of said positions, and means 35 for limiting movement of said guiding member in either direction.

104. In a mining machine of the invertible type having a machine frame presenting parallel plane supporting surfaces on which the machine is adapted to be selectively supported, feeding means for the machine including a feed operating member rotatable on an axis lying in a vertical plane extending 40 longitudinally of the machine and a cooperating flexible element, and means for guiding said element including a swingable guiding member disposable adjacent either supporting surface of said frame.

105. In a mining machine of the invertible

type having a machine frame presenting parallel plane supporting surfaces on which the machine is adapted to be selectively supported, feeding means for the machine including a feed operating member rotatable on an axis lying in a vertical plane extending longitudinally of the machine and a cooperating flexible element, and means for guiding said element including a swingable guiding member disposable adjacent either supporting surface of said frame to permit said flexible element to be extended from the machine when disposed in different planes. 70

106. In a mining machine, an invertible machine frame presenting parallel plane supporting surfaces on which the machine is adapted to be selectively supported, reversible cutting mechanism including a rigid forwardly projecting cutter bar, and feeding means including feed operating members having their axes lying in vertical planes extending longitudinally of the machine and a cooperating flexible element for feeding the machine laterally in opposite directions while supported on either of said supporting surfaces. 80

107. In a mining machine, an invertible machine frame presenting parallel plane supporting surfaces on which the machine is adapted to be selectively supported, and means for feeding the machine while supported on either surface thereof comprising a plurality of feed operating members having their axes lying in planes parallel with a vertical plane extending longitudinally of the machine, and flexible feeding means cooperating therewith. 95

108. In a mining machine, an invertible machine frame presenting parallel plane supporting surfaces on which the machine is adapted to be selectively supported, and means for feeding the machine while supported on either surface thereof comprising a plurality of feed operating members rotatable on parallel axes, and flexible feeding means cooperating therewith. 105

109. In a mining machine, an invertible machine frame presenting parallel plane supporting surfaces on which the machine is adapted to be selectively supported, and means for feeding the machine while supported on either surface thereof comprising a plurality of feed operating members rotatable on parallel axes extending longitudinally of the machine, and flexible feeding means cooperating therewith. 115

110. In a mining machine, a driving motor, and feeding means driven thereby including a plurality of feed operating members rotatable on parallel axes and adapted to cooperate with flexible feeding means, and means for driving each of said members at fast or slow speed including separate fast and slow speed controlling means individual to each of said members. 125

111. In a mining machine, a driving motor, and feeding means driven thereby including a plurality of feed operating members rotatable on parallel axes extending longitudinally of the machine and adapted to cooperate with flexible feeding means, and separate fast and slow speed controlling means for said members.
112. In a mining machine, a driving motor, and feeding means driven thereby comprising a plurality of feed operating members adapted to cooperate with flexible feeding means, and fast and slow speed driving means for each of said members including a plurality of driving worms rotatable on vertical axes at the longitudinal center of the machine.
113. In a mining machine, an invertible machine frame presenting parallel plane supporting surfaces on which the machine is adapted to be selectively supported, and feeding means for the machine including feed operating members disposed at the rear end of said frame and each rotatable on an axis extending longitudinally of the machine.
114. In a mining machine, an invertible machine frame presenting parallel plane supporting surfaces on which the machine is adapted to be selectively supported, and truck driving means including independently operable truck driving elements operative to drive a truck while the machine is supported on either supporting surface thereof.
115. In a mining machine, a feed operating member adapted to cooperate directly with a flexible feeding member and rotatable about an axis disposed in a plane extending longitudinally of the machine, driving means therefor including a shaft disposed coaxially with said axis, a second shaft disposed transversely of and laterally offset from said axis, and a worm on one shaft and a worm gear on the other shaft, said gears meshing together.
116. In a mining machine, a driving motor and feeding means driven by said motor including a plurality of relatively rotatable feed operating members each adapted to cooperate with flexible feeding means, and a plurality of speed controlling clutches a plurality of which are individual to and disposed coaxially with each of said feed operating members.
117. In a mining machine, a driving motor and feeding means driven thereby including a plurality of relatively rotatable feed operating members each adapted to cooperate with flexible feeding means, and a friction speed controlling clutch individual to and disposed coaxially with each of said feed operating members.
118. In a mining machine, a driving motor and feeding means driven thereby including a plurality of relatively rotatable feed operating members rotatable on axes lying in planes parallel to a vertical plane extending longitudinally of the machine, each adapted to cooperate with flexible feeding means, and separate fast and slow speed controlling means for each of said feed operating members.
119. In a mining machine, a driving motor and feeding means driven thereby including a plurality of relatively rotatable feed operating members rotatable on axes lying in planes parallel to a vertical plane extending longitudinally of the machine, each adapted to cooperate with flexible feeding means, and separate fast and slow speed controlling means for each of said feed operating members including coaxial controlling clutches disposed on axes extending longitudinally of the machine.
120. In a mining machine, a driving motor and feeding means driven thereby comprising a plurality of relatively rotatable feed operating members each adapted to cooperate with flexible feeding means, and fast and slow speed driving means for each of said members including a plurality of driving worms rotatable on parallel axes, and worm gears meshing with said worms, said worm gears being selectively operable as driving members for that one of said feed operating members of whose drive they form a part.
121. In a mining machine, a driving motor and feeding means driven thereby comprising a plurality of relatively rotatable feed operating members each adapted to cooperate with flexible feeding means, and fast and slow speed driving means for each of said members including a plurality of driving worms rotatable on parallel axes extending transversely of the machine, and worm gears meshing with said worms, said worm gears being selectively operable as driving members for that one of said feed operating members of whose drive they form a part.
122. In a mining machine, feeding means therefor including a feed operating member adapted to cooperate with flexible feeding means, a plurality of friction clutches disposed on axes parallel to a line parallel to the axis of said feed operating member, and means for selectively applying said clutches including a pivoted shipper member and a resilient mounting for said shipper member.
123. In a mining machine, a motor and feeding means driven thereby including a shaft, worm gears coaxial with said shaft, clutches for selectively connecting said worm gears to said shaft, a feed operating member adapted to cooperate with flexible feeding means, driving connections between said feed operating member and said shaft, and means for actuating said clutches including a pivoted shipper member and a resilient pivotal mounting for said shipper member.
124. In a mining machine, a motor and feeding means driven thereby including a feed operating member rotatable on an axis

lying in a vertical plane extending longitudinally of the machine and adapted to cooperate with flexible feeding means, and driving means between said motor and said feed operating member including coaxial fast and slow speed worm gears rotatable on axes lying in a vertical plane extending longitudinally of the machine and selectively operative to drive said feed operating member at a fast or at a slow speed.

125. In a mining machine, a motor and feeding means driven thereby including a feed operating member rotatable on an axis lying in a vertical plane extending longitudinally of the machine and adapted to cooperate with flexible feeding means, driving means between said motor and said feed operating member including coaxial fast and slow speed worm gears rotatable on axes lying in a vertical plane extending longitudinally of the machine and selectively operative to drive said feed operating member at a fast or at a slow speed, and worms rotating on parallel axes and meshing with said worm gears.

126. In a mining machine, a motor and feeding means driven thereby including a feed operating member rotatable on an axis lying in a vertical plane extending longitudinally of the machine and adapted to cooperate with flexible feeding means, driving means between said motor and said feed operating member including coaxial fast and slow speed worm gears rotatable on axes lying in a vertical plane extending longitudinally of the machine and selectively operative to drive said feed operating member at a fast or at a slow speed, and worms rotating on parallel axes extending transversely of the machine and meshing with said worm gears.

127. In a mining machine, a motor and feeding means driven thereby including a feed operating member rotatable on an axis lying in a vertical plane extending longitudinally of the machine and adapted to cooperate with flexible feeding means, driving means between said motor and said feed operating member including coaxial fast and slow speed worm gears rotatable on axes lying in a vertical plane extending longitudinally of the machine and selectively operative to drive said feed operating member at a fast or at a slow speed, worms rotating on parallel axes and meshing with said worm gears, and intermeshing gearing connecting said worms together for simultaneous rotation.

128. In a mining machine, a motor and feeding means driven thereby including a feed operating member rotatable on an axis lying in a vertical plane extending longitudinally of the machine and adapted to cooperate with flexible feeding means, driving means between said motor and said feed operating member including coaxial fast and

slow speed worm gears rotatable on axes lying in a vertical plane extending longitudinally of the machine and selectively operative to drive said feed operating member at a fast or at a slow speed, and worms rotating on parallel axes extending transversely of the machine and meshing with said worm gears, and intermeshing gearing connecting said worms together for simultaneous rotation.

129. In a mining machine, a motor and feeding means driven by said motor including a plurality of relatively rotatable feed operating members each adapted to cooperate with flexible feeding means, said feed operating members being rotatable on axes lying in planes parallel to a vertical plane extending longitudinally of the machine, and driving means between said motor and said feed operating members including coaxial fast and slow speed worm gears selectively operative to drive one of said members at a fast or a slow speed.

130. In a mining machine, a motor and feeding means driven by said motor including a plurality of relatively rotatable feed operating members each adapted to cooperate with flexible feeding means, said feed operating members being rotatable on axes lying in planes parallel to a vertical plane extending longitudinally of the machine, driving means between said motor and said feed operating members including coaxial fast and slow speed worm gears selectively operative to drive one of said members at a fast or a slow speed, and worms rotating on parallel axes and meshing with said worm gears.

131. In a mining machine, a motor and feeding means driven by said motor including a plurality of relatively rotatable feed operating members each adapted to cooperate with flexible feeding means, said feed operating members being rotatable on axes lying in planes parallel to a vertical plane extending longitudinally of the machine, driving means between said motor and said feed operating members including coaxial fast and slow speed worm gears selectively operative to drive one of said members at a fast or a slow speed, and worms rotating on parallel axes extending transversely of the machine and meshing with said worm gears.

132. In a mining machine of the type which is slidable over the mine bottom during cutting, a motor and feeding means for moving the machine upon the mine bottom parallel to a working face driven by said motor and including a feed operating member adapted to cooperate with flexible feeding means, and driving connections between said feed operating member and said motor including coaxial worm gears rotatable on axes lying in a vertical plane extending longitudinally of the machine and selectively

operative to drive said feed operating member at a fast or a slow speed.

133. In a mining machine of the type which is slidable over the mine bottom during cutting, a motor and feeding means for moving the machine upon the mine bottom parallel to a working face driven by said motor and including a feed operating member adapted to cooperate with flexible feeding means, and driving connections between said feed operating member and said motor including coaxial worm gears rotatable on axes lying in a vertical plane extending longitudinally of the machine and selectively operative to drive said feed operating member at a fast or a slow speed, and worms rotating on parallel axes and meshing with said worm gears.

134. In a mining machine of the type which is slidable over the mine bottom during cutting, a motor and feeding means for moving the machine upon the mine bottom parallel to a working face driven by said motor and including a feed operating member adapted to cooperate with flexible feeding means, and driving connections between said feed operating member and said motor including coaxial worm gears rotatable on axes lying in a vertical plane extending longitudinally of the machine and selectively operative to drive said feed operating member at a fast or a slow speed, and worms rotating on parallel axes extending transversely of the machine and meshing with said worm gears.

135. In a mining machine, a motor and feeding means driven by said motor including a plurality of relatively rotatable feed operating members each adapted to cooperate with flexible feeding means, and driving connections between said feed operating members and said motor including coaxial worm gears rotatable on axes lying in a vertical plane extending longitudinally of the machine, said worm gears being selectively operative to drive one of said feed operating members at a fast or a slow speed.

136. In a mining machine, a motor and feeding means driven by said motor including a plurality of relatively rotatable feed operating members each adapted to cooperate with flexible feeding means, driving connections between said feed operating members and said motor including coaxial worm gears rotatable on axes lying in a vertical plane extending longitudinally of the machine, said worm gears being selectively operative to drive one of said feed operating members at a fast or a slow speed, and worms rotating on parallel axes and meshing with said worm gears.

137. In a mining machine, a motor and feeding means driven by said motor including a plurality of relatively rotatable feed operating members each adapted to cooperate with flexible feeding means, driving connections

between said feed operating members and said motor including coaxial worm gears rotatable on axes lying in a vertical plane extending longitudinally of the machine, said worm gears being selectively operative to drive one of said feed operating members at a fast or a slow speed, and worms rotating on parallel axes extending transversely of the machine and meshing with said worm gears.

138. In a mining machine, a motor and feeding means driven by said motor including a feed operating member rotatable on an axis lying in a vertical plane extending longitudinally of the machine and adapted to cooperate with flexible feeding means, driving means between said motor and feed operating member including coaxial fast and slow speed worm gears rotatable on axes lying in a vertical plane extending longitudinally of the machine and selectively operative to drive said feed operating member at a fast or a slow speed, and a manually controllable clutch between said worm gearing and said feed operating member.

139. In a mining machine, a motor and feeding means driven by said motor including a plurality of relatively rotatable feed operating members each adapted to cooperate with flexible feeding means, said members being rotatable on axes lying in planes parallel to a vertical plane extending longitudinally of the machine, and driving means between said motor and said feed operating members including coaxial fast and slow speed worm gears selectively operative to drive one of said members at a fast or a slow speed, and manually controllable clutch means between said worm gearing and said feed operating members.

140. In a mining machine, a motor and feeding means driven by said motor including a feed operating member rotatable on an axis lying in a vertical plane extending longitudinally of the machine and adapted to cooperate with flexible feeding means, and driving means between said motor and feed operating member including coaxial fast and slow speed worm gears selectively operative to drive said feed operating member at a fast or a slow speed, and a manually controllable clutch between said worm gearing and said feed operating member and arranged coaxially with the latter.

141. In a mining machine, a motor and feeding means driven by said motor including a plurality of relatively rotatable feed operating members each adapted to cooperate with flexible feeding means, said members being rotatable on axes lying in planes parallel to a vertical plane extending longitudinally of the machine, and driving means between said motor and said feed operating members including coaxial fast and slow speed worm gears selectively operative to drive one of said members at a fast or a slow

- speed, and manually controllable clutch means between said worm gearing and said feed operating members including a clutch arranged coaxially with one of said feed operating members.
142. In a mining machine, a motor, feeding means driven thereby including a plurality of relatively rotatable feed operating members at the same end of the machine and each adapted to cooperate with flexible feeding means, driving connections between said motor and said feed operating members including variable speed driving means providing a plurality of predetermined speeds, and separate planetary driving means one between said variable speed driving means and each of said feed operating members.
143. In a mining machine, a motor, feeding means driven thereby including a plurality of relatively rotatable feed operating members each adapted to cooperate with flexible feeding means, driving connections between said motor and said feed operating members including variable speed driving means having a plurality of predetermined speeds, separate planetary driving means one between said variable speed driving means and each of said feed operating members, and a manually controllable clutch arranged coaxially with each of said feed operating members for connecting the same to said planetary driving means.
144. In a mining machine, a motor, feeding means driven thereby including a plurality of relatively rotatable feed operating members each adapted to cooperate with flexible feeding means, driving connections between said motor and said feed operating members including variable speed driving means including fast and slow speed clutches coaxial with each of said feed operating members, and a separate planetary driving means between said variable speed driving means and each of said feed operating members.
145. In a mining machine, a horizontal driving motor having its axis extending longitudinally of the machine and feeding means driven thereby including a feed operating member rotatable on an axis lying in a vertical plane extending longitudinally of the machine and adapted to cooperate directly with a flexible feeding member, and driving connections between said motor and said feed operating member including a worm driving gear disposed on an axis parallel to a line parallel with the axis of said feed operating member and a friction controlling clutch coaxial with said worm gear.
146. In a mining machine, a horizontal driving motor having its axis extending longitudinally of the machine, and feeding means driven thereby including a feed operating member rotatable on an axis lying in a vertical plane extending longitudinally of the machine and adapted to cooperate with flexible feeding means, and driving connections between said motor and said feed operating member including a worm driving gear disposed on an axis parallel to a line parallel with the axis of said feed operating member and a friction controlling clutch coaxial with said worm gear.
- chine and adapted to cooperate with flexible feeding means, and driving connections between said motor and said feed operating member including coaxial fast and slow speed worm driving gears disposed on axes parallel to a line parallel with the axis of said feed operating member, said gears being selectively operable to drive said member at fast or slow speeds.
147. In a mining machine, feeding mechanism for the machine as a whole including clutches axially movable in parallel lines to effect feeding, and means including relatively rotatable control members manually rotatable on a common axis for actuating said clutches.
148. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed including separate frictionally controlled fast and slow predetermined speed gear trains for each member.
149. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed or to permit rotation of said members in a direction to pay out said flexible feeding means under various degrees of frictional resistance, said mechanism including separate frictionally controlled fast and slow predetermined speed gear trains for each member.
150. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means.

- means either separately or simultaneously at a relatively high speed or at a relatively low speed or to permit rotation of said members in a direction to pay out said flexible feeding 5 means under various degrees of frictional resistance or without such resistance, said mechanism including separate frictionally controlled fast and slow predetermined speed gear trains for each member.
151. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed including separate fast and slow speed 25 worm gear trains for each member.
152. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed or to permit rotation of said members in a direction to pay out said flexible feeding means under various degrees of frictional resistance, said mechanism including separate fast and slow speed worm 40 gear trains for each member and each train having its individual friction controlling means.
153. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed or to permit rotation of said members in a direction to pay out said flexible feeding means under various degrees of frictional resistance or without such re- 55 sistance, said mechanism including separate fast and slow speed worm gear trains for each member and each train having its individual friction controlling means.
154. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed including separate fast and slow speed worm gear trains for each member and a separate friction controlling clutch individual to and for controlling each train.
155. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed or to permit rotation of said members in a direction to pay out said flexible feeding means under various degrees of frictional resistance, said mechanism including separate fast and slow speed worm gear trains for each member and a separate friction controlling clutch individual to and for controlling each train.
156. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means, and mechanism for effecting rotation of said members in a direction to draw in said flexible feeding means either separately or simultaneously at a relatively high speed or at a relatively low speed or to permit rotation of said members in a direction to pay out said flexible feeding means under various degrees of frictional resistance or without such resistance, said mechanism including separate fast and slow speed worm gear trains for

each member and a separate friction controlling clutch individual to and for controlling each train.

157. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each of said members for effecting rotation of said members at a plurality of different predetermined speeds.

158. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each of said members for effecting rotation of said members either separately or simultaneously at a plurality of different predetermined speeds.

159. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each of said members for effecting rotation of said members either separately or simultaneously in a direction to draw in said flexible feeding means at a plurality of different predetermined speeds.

160. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each of said members for effecting rotation of said members either separately or simultaneously in a direction to draw in said flexible feeding means at a plurality of different predetermined speeds or to permit rotation of said members in a direction to pay out said flexible feeding means under various degrees of frictional resistance.

161. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each of said members for effecting rotation of said members either separately or simul-

taneously in a direction to draw in said flexible feeding means at a plurality of different predetermined speeds or to permit rotation of said members in a direction to pay out said flexible feeding means under various degrees of frictional resistance or without such resistance.

162. In a mining machine, a driving motor and feeding means driven by said motor including relatively rotatable feed operating and controlling members each adapted to cooperate directly with flexible feeding means, and driving mechanism for said members including a plurality of speed controlling clutches, a plurality of which are individual to each member for effecting rotation of said members simultaneously in opposite directions to draw in said flexible feeding means at a plurality of different predetermined speeds.

163. In a mining machine, a driving motor and feeding means driven by said motor including relatively rotatable feed operating and controlling members each adapted to cooperate directly with flexible feeding means, and driving mechanism for said members including a fast speed gear train and a slow speed gear train for each member through which it, but not the other, is driven, each of said trains including a terminal gear and all of said terminal gears being rotatable on axes parallel to a line parallel with the axes of said members.

164. In a mining machine, a driving motor and feeding means driven by said motor including relatively rotatable feed operating and controlling members each adapted to cooperate directly with flexible feeding means, and driving mechanism for said members including a fast speed gear train and a slow speed gear train for each member through which it, but not the other, is driven, each of said trains including a terminal gear and all of said terminal gears being rotatable on axes parallel to a line parallel with the axes of said members, and a friction clutch for connecting each terminal gear in driving relation with its respective member.

165. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means and plural speed driving mechanism for said members including a separate and distinct two-speed drive for each member, each of said two speed drives having a plurality of selectively operable friction controlling clutches.

166. In a mining machine, a machine

frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means and plural speed driving mechanism for said members including a separate and distinct two-speed drive for each member including fast and slow speed worm gear trains having their terminal worm wheels coaxially arranged.

167. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means and plural speed driving mechanism for said members including a separate and distinct two-speed drive for each member including fast and slow speed worm gear trains having their terminal worm wheels coaxially arranged and disposed on axes parallel to a line parallel to the axes of said feed operating and controlling members.

168. In a mining machine, a machine frame adapted to rest upon and slide in any direction over the mine bottom, a motor carried by said frame, cutting mechanism driven by said motor including an elongated kerf cutter projecting from said frame, and feeding means driven by said motor including relatively rotatable feed operating and controlling members each adapted to cooperate directly with flexible feeding means and plural speed driving mechanism for said members including a separate and distinct two-speed drive for each member including fast and slow speed worm gear trains having their terminal worm wheels coaxially arranged and disposed on axes parallel to a line parallel to the axes of said feed operating and controlling members, and a friction clutch for controlling the connection of each worm wheel with its respective member.

169. In a mining machine, a machine frame adapted to rest upon and slide in any direction over the mine bottom, a driving motor carried by said frame, cutting mechanism driven by said motor including an elongated kerf cutter projecting from said frame, and feeding means driven by said motor including relatively rotatable feed operating and controlling members each adapted to cooperate directly with flexible feeding means and rotatable on axes lying in parallel vertical planes extending longitudinally of the ma-

chine at opposite sides of the longitudinal vertical center of the machine, and driving and controlling mechanism for said members for effecting rotation thereof either separately or simultaneously in a direction to draw in said flexible feeding means and including separate and distinct driving gearing for each member.

170. In a mining machine, a machine frame adapted to rest upon and slide in any direction over the mine bottom, a driving motor carried by said frame, cutting mechanism driven by said motor including an elongated kerf cutter projecting from said frame, and feeding means driven by said motor including relatively rotatable feed operating and controlling members each adapted to cooperate directly with flexible feeding means and rotatable on axes lying in parallel vertical planes extending longitudinally of the machine at opposite sides of the longitudinal vertical center of the machine, and driving and controlling mechanism for said members for effecting rotation thereof either separately or simultaneously in a direction to draw in said flexible feeding means at a relatively low speed or at a relatively high speed and including a separate and distinct plural predetermined speed drive for each member.

171. In a mining machine, a machine frame adapted to rest upon and slide in any direction over the mine bottom, a driving motor carried by said frame, cutting mechanism driven by said motor including an elongated kerf cutter projecting from said frame, and feeding means driven by said motor including relatively rotatable feed operating and controlling members each adapted to cooperate directly with flexible feeding means and rotatable on axes lying in parallel vertical planes extending longitudinally of the machine at opposite sides of the longitudinal vertical center of the machine, and driving and controlling mechanism for said members for effecting rotation thereof either separately or simultaneously in a direction to draw in said flexible feeding means at a relatively low speed or at a relatively high speed, or to permit said members to revolve in a direction to pay out said flexible feeding means under various degrees of frictional resistance and including a separate and distinct plural predetermined speed drive for each member.

172. In a mining machine, a machine frame adapted to rest upon and slide in any direction over the mine bottom, a driving motor carried by said frame, cutting mechanism driven by said motor including an elongated kerf cutter projecting from said frame, and feeding means driven by said motor including relatively rotatable feed operating and controlling members each adapted to cooperate directly with flexible feeding means and rotatable on axes lying in parallel vertical planes extending longitudinally of the ma-

chine at opposite sides of the longitudinal vertical center of the machine, and driving and controlling mechanism for said members for effecting rotation thereof either separately or simultaneously in a direction to draw in said flexible feeding means at a relatively low speed or at a relatively high speed, or to permit said members to revolve in a direction to pay out said flexible feeding means under various degrees of frictional resistance or without such resistance and including a separate and distinct plural predetermined 10 speed drive for each member.

173. In a mining machine, a machine frame 15 adapted to rest upon and slide in any direction over the mine bottom, a motor carried by said frame, cutting mechanism driven by said motor including an elongated kerf cutter projecting from said frame, and feeding 20 means driven by said motor including relatively rotatable winding members of the same size and diameter and rotatable at like peripheral speeds, said winding members being disposed on the opposite sides of the longitudinal vertical center of the machine, one on the advancing side of the machine and the other on the receding side thereof, and each 25 adapted to cooperate directly with flexible feeding means, and mechanism for effecting 30 rotation of said winding members in a direction to draw in said flexible feeding means either separately or simultaneously at relatively high speed or at relatively low speed, said mechanism including a separate and distinct fast and slow transmission gearing for 35 each member through which it, but not the other member, is driven.

174. In a mining machine, a machine frame 40 adapted to rest upon and slide in any direction over the mine bottom, a motor carried by said frame, cutting mechanism driven by said motor including an elongated kerf cutter projecting from said frame, and feeding means driven by said motor including relatively rotatable winding members of the same size and diameter and rotatable at like peripheral speeds, said winding members being disposed on the opposite sides of the longitudinal vertical center of the machine, one on the 45 advancing side of the machine and the other on the receding side thereof, and each adapted to cooperate directly with flexible feeding means, and mechanism for effecting rotation of said winding members in a direction to 50 draw in said flexible feeding means either separately or simultaneously at relatively high speed or at relatively low speed or to permit said winding members to revolve in a direction to pay out said flexible feeding 55 means under various degrees of frictional resistance, said mechanism including a separate and distinct fast and slow transmission gearing for each member through which it, but not the other member, is driven.

60 175. In a mining machine, a machine frame

adapted to rest upon and slide in any direction over the mine bottom, a motor carried by said frame, cutting mechanism driven by said motor including an elongated kerf cutter projecting from said frame, and feeding 70 means driven by said motor including relatively rotatable winding members of the same size and diameter and rotatable at like peripheral speeds, said winding members being disposed on the opposite sides of the longitudinal vertical center of the machine, one on the advancing side of the machine and the other on the receding side thereof, and each 75 adapted to cooperate directly with flexible feeding means, and mechanism for effecting rotation of said winding members in a direction to draw in said flexible feeding means either separately or simultaneously at relatively high speed or at relatively low speed 80 or to permit said winding members to revolve in a direction to pay out said flexible feeding means under various degrees of frictional resistance or without such resistance, said mechanism including a separate and distinct fast and slow transmission gearing for each 85 member through which it, but not the other member, is driven.

In testimony whereof I affix my signature.
MORRIS P. HOLMES.
